UNITED STATES PATENT OFFICE.

HENRY POLCEK, OF NEW YORK, N. Y.

SAFETY WINDOW-LOCK.

1,352,624.

Specification of Letters Patent. Patented Sept. 14, 1920.

Application filed January 7, 1920. Serial No. 349,914.

To all whom it may concern:

Be it known that I, HENRY POLCEK, a citizen of the United States, and resident of New York city, in the county of New York and State of New York, have invented certain new and useful Improvements in Safety Window-Locks, of which the following is a specification.

This invention relates to new and useful 10 improvements in window locks and more particularly to a lock which may not be tampered with from the outside of the window.

Another object of my invention resides in 15 providing a device which will positively lock a window.

A further object of my invention is to provide a device which may not only be unlocked from that side of the sash on which 20 the handle or knob is provided, but which will resist its unlocking operation unless the knob is turned in a desired direction.

With these and other objects in view, the invention consists in the novel features of 25 construction, combination and arrangement of parts as will be more fully apparent in the following description and from the accompanying drawings, forming part of this specification, in which:

30 Figure 1 is a sectional view of my device in partially locked position.

Fig. 2 is a top view of the housing.

Fig. 3 is a front elevation of same.

Fig. 4 is a side elevation of same.

35 Fig. 5 is a bottom view of same.

Fig. 6 is an enlarged detail bottom view of the housing showing the lock-bolt in partially locked position, corresponding to Fig. 1.

40 Fig. 7 is a top view of a socket.

Fig. 8 represents my device in a totally locking position.

Fig. 9 represents my device in disengaged position.

45 Fig. 10 is an elevation showing a window with my device attached.

Referring to the drawings, 10 designates one window sash through which passes the operative part of my device, 11 is another 50 window sash or cross member in which lodges the inoperative portion of my lock.

The housing, shown in various views in Figs. 2, 3, 4, and 5, comprises a fastening plate 12 provided with countersunk holes 13 for receiving screws or other fastening means 14, by means of which the plate is

attached to cross member 10. Extending outward from plate 12 is a conically shaped neck or extension 15, having an aperture 16. Opposite the neck and adjacent to the attaching face of plate 12 is a tubular member 17 adapted to pass through sash 10 preferably at its center, as may be seen in Fig. 10. The tubular member possesses a pair of opposite disposed longitudinal slots 18, terminating at the free end of the cylinder into peripheral recesses 19, as may be clearly seen in Figs. 5 and 6.

Opposite the open end of the tubular member 17 and attached to the other sash 11 of the window, is a socket comprising a fastening plate 20 provided with countersunk holes 21 for receiving screws or other attaching means 22. Extending from the plate 20 into and to about half the width of the sash 75 is thimble 23 with a chamfered edge 24 at its open end.

Guided in the cylindrical opening 16 of the neck piece 15 is a lock-bolt 25 equipped at one end with a substantially conically shaped knob or handle 26, and provided at its other end with a cone-shaped point 27. The reduced portion of the knob possesses a nut-like, flat portion 28 adapted to bear or rest against the reduced portion of neck 15. 85

Passing through the bolt 25 and registering with the recesses 19 of the tubular member 17 of the housing is a pin 29 against which bears a coil-spring 30 at one end, the other end of which rests in a recess 31 provided at the broader portion of neck 15. 90

When the window is to be locked, the meeting sashes 10 and 11 are brought in position shown in Figs. 9 and 10, while the bolt is turned and pulled out by way of the 95 knob in such a way as to cause the pin 29 to enter the guide-slots 18. By pulling the knob, the spring 30 is compressed. When now the sashes are in position and the thimble opening faces the bolt, the knob is released, and the bolt is permitted to enter the socket. Then the knob is turned causing pin 29 to engage the recesses 19 as indicated in dashed and dotted lines in Fig. 6.

Any attempt to unlock the window from the outside that is from the opposite side of the sash on which the knob is provided will prove useless.

I am aware of the existence of a number of patents on similar devices and I herewith 110 disclaim same restricting my invention to the general construction and combination

of parts as shown in the drawings and described and claimed in this specification.

I reserve however for myself the right to make improvements or changes within the scope of my invention to meet various conditions.

What I claim is:

In a sash fastener, the combination with meeting cross members of an outer and an inner window frame, a housing comprising a tubular receiver, adapted to pass through one of said cross members, having a pair of opposite disposed longitudinal guide-slots terminating into a pair of peripheral stop-recesses open at the extreme end of said tubular receiver, a fastening plate forming an integral part of said receiver, a conical neck extending opposite said receiver from said plate; a socket, having a similar fas-

tening plate, adapted to be attached to said other cross member, a lock-bolt having a large hand knob at one end, adapted for turning and pulling said bolt, a conically shaped point provided at the other end of the bolt normally extending into said socket, a pin passing through said bolt and extending into said slots, a spring bearing against said pin and a seat provided in said neck, said spring causing said bolt to normally protrude with its pointed end into said socket, said bolt being prevented from leaving said socket when its knob is turned and said pin engages said peripheral recesses of said tubular receiver.

Signed at New York city, in the county of New York, and State of New York, this 3rd day of January A. D. 1920.

HENRY POLCEK.
